Fig 4

5—

Fig 5

FIG. 1 is a top plan view of a handled support stand for a cooking vessel embodying my new design;

FIG. 2 is a bottom plan view thereof;

FIG. 3 is a side elevational view thereof;

FIG. 4 is an end elevational view thereof;

FIG. 5 is a cross-sectional view taken along line 5—5 of FIG. 4.

I claim:

The ornamental design for a handled support stand for a cooking vessel, as shown.
